(57) **CLAIM**

The ornamental design for a tailgate gap cover, as shown and described.

DESCRIPTION

FIG. 1 is a top perspective view of a tailgate gap cover, showing my new design;

FIG. 2 is a top plan view thereof;

FIG. 3 is a bottom plan view thereof;

FIG. 4 is a back side view thereof;

FIG. 5 is a front side view thereof;

FIG. 6 is a right side view thereof;

FIG. 7 is a left side view thereof; and,

FIG. 8 is a top perspective view of the tailgate gap cover of FIG. 1 attached to a truck and spanning the truck bed and the tailgate.

The trademark material containing the words “GAP FLAP” is owned by the inventor and is not a registered trademark. The truck bed and the tailgate shown in broken lines in FIG. 8 is included to show environment that form no part of the claimed design.
